Filed Dec. 28, 1959, Ser. No. 58,821

Term of patent 14 years

(Cl. D58—12)

FIG. 1

FIG. 2

Figure 1 is a perspective view of a container for magnetic tape reel, embodying my new design;

Figure 2 is a side elevational view thereof;

Figure 3 is an edge elevational view thereof taken from the rightside of Figure 2;

Figure 4 is an elevational view of the opposite side thereof, reversed from top to bottom from the position shown in Figure 2;

Figure 5 is an edge elevational view thereof taken from the leftside of Figure 2; and

Figure 6 is a cross-sectional view taken through line 6-6 of Figure 2.

The bottom edge not shown is the same as the edge view shown in Figure 5.

I claim:

The ornamental design for a container for magnetic tape reel, substantially as shown and described.
